UNITED STATES PATENT OFFICE.

ALOIS FUCHS, OF MOR.-OSTRAVA, CZECHOSLOVAKIA.

SHEET-METAL RADIATOR.

Application filed December 2, 1926, Serial No. 152,138, and in Czechoslovakia December 3, 1925.

The use of tin plates for radiators has not been possible until now, as the members of the radiators, when made of tin, are not rigid enough at the places where they had to be connected. As all the motions, produced by transport or by heating, are transmitted to these places of connection, the sections of a radiator would move relative to each other and the effect would be that the places of connection would be loosened.

The object of the invention is to obviate these drawbacks by making the members of each section of the radiator between the connecting means at each end of the section (openings of the radiator) of convolute form, so that deforming of a radiator is prevented, a distribution of the heating fluid takes place and the radiator is made resistant to great pressures.

Another object of the invention is to provide an improved form of connecting means wherein the connecting tube and its ring member are held together and secured to the section of a radiator by means of a pin.

In the drawing, the subject matter of the invention is shown in one constructional form, by way of example.

Fig. 1 is a fragmentary plan view of one of the members of a section of the radiator;

Fig. 2 is a sectional view of one section of the radiator taken on the line *a*—*b* of Fig. 1;

Fig. 3 is a similar view taken on the line *c*—*d* of Fig. 1;

Fig. 4 is an enlarged longitudinal section of one of the connecting means; and

Fig. 5 is a section taken at right angles to Fig. 4.

By forming the tin plate members of the section of the radiator with convolutions, channels 1 of different lengths connected by strips 2 are effected. When two of such plates or members are placed together, as shown in Fig. 3, the channels 1 will form tubes, while the strips 2 are welded together by means of special machines.

By means of these tubes, which are spaced equidistances apart, a register of tubes is formed and the heating fluid is divided while passing therethrough in such manner that a perfect distribution of the fluid is effected resulting in the utilization of its full heating capacity. The channels 1 communicate with chambers in the upper and lower part of each section. These chambers are formed by depressions 3 and permit of an upper and lower distribution of the fluid, the abutting depres-

sions serving to reinforce the upper and lower parts of the radiator section. By means of these depressions 3 and the strips 2, a perfect reinforcing around the openings of the radiator is obtained. The depressions 3 are arranged on opposite sides and at the level of openings 3' to which the connecting pipes (not shown) are joined for the purpose of circulating liquid through the radiator, and the channels terminate adjacent said openings and depressions with the ends of longer channels extending a slight distance between the openings 3' and the depressions 3.

The sections of the radiator can be connected by means affording reinforcement between sections and preventing any relative movement between the same.

In openings 4 of the connection tube 7 and connecting ring 8 of each connecting means, designed for the passage of the heating fluid, there is mounted a pin 5. This pin 5 can have a round or an angular form, according to the forms of the openings 4. This connection, provided with the pin 5, is put between the plates of the radiator section, before these latter are welded together, in such manner that the pinhead 6 engages the inside surfaces of the plates, preventing thus a distortion or a falling-out of the connecting means.

As shown in Figs. 4 and 5, each connecting means consists of two parts, the internally threaded connection tube 7 and the connecting ring 8. These two parts can be made of different material, that of the connection tube 7 being made of a material of great strength to resist expansion and the connecting ring 8 being made of a material of great strength to resist pressure. The tube 7 and the ring 8 are connected by the pin 5, put into corresponding aligned openings 4.

The tube 7 is surrounded by the ring 8 and at its ends by spacing sleeves 9, and can be therefore made of rolled tin plates without welding joint.

Radiators according to this invention, provided with tubes formed by means of convolutions in the members of the sections, can be made of tin plates of the thickness of 0.6-1 mm. and can resist the greatest pressure without being injured.

I claim:

1. In a radiator, a pair of opposed sections, a connecting means therefor including a connecting tube having openings therein, a ring member encircling said tube and having openings aligned with those in said tube, and

- a pin engaging in two of said aligned openings and having a head engageable with adjacent portions of said sections of the radiator.
5. 2. In a radiator, a pair of opposed sections, a connecting means therefor including a connecting tube having openings therein, a ring member encircling said tube and having openings aligned with those in said tube, a 10 a pin engaging in two of said aligned openings and having a head engageable with adjacent portions of said sections of the radiator, and spacing sleeves encircling said tube on opposite sides of said ring member.
15. 3. A radiator of thin sheet metal including a sectional body having openings therein, the sections of said body being provided with convolutions having abutting portions between which are formed channels of different lengths in the radiator, and being further 20 provided with depressions forming chambers at the ends of the radiator on opposite sides of and adjacent said openings, and the ends of said channels terminating adjacent said openings and depressions with the ends of the 25 longer channels extending a distance between said openings and depressions.

In testimony whereof I affix my signature.

ALOIS FUCHS.
